[57] CLAIM

The ornamental design for a spacesaver cabinet, as shown
and described.

DESCRIPTION

FIG. 1 is a perspective view of a spacesaver cabinet showing
our new design;

FIG. 2 is a front elevational view thereof;

FIG. 3 is a top plan view thereof;

FIG. 4 is a left side view thereof, the opposite side being a
mirror image of the side shown; and,

FIG. 5 is a rear elevational view thereof.
